CLAIM

The ornamental design for a drawer unit as shown and described.

DESCRIPTION

FIG. 1 is a top, front, left side perspective view of a drawer unit, showing a first embodiment of our new design in a first configuration of use;

FIG. 2 is a top, front, left side perspective view thereof, shown in a second configuration of use;

FIG. 3 is a bottom, back, left side perspective view thereof;

FIG. 4 is a front view thereof;

FIG. 5 is a back view thereof;

FIG. 6 is a left side view thereof;

FIG. 7 is a right side view thereof;

FIG. 8 is a top view thereof;

FIG. 9 is a bottom view thereof;

FIG. 10 is a top, front, left side perspective view thereof, shown in a third configuration of use;

FIG. 11 is a bottom, back, left side perspective view thereof;

FIG. 12 is an enlarged view of detail 12 in FIG. 10;

FIG. 13 is an enlarged view of detail 13 in FIG. 11;

FIG. 14 is an exploded perspective view thereof;

FIG. 15 is a top, front, left side perspective view of a drawer unit, showing a second embodiment of our new design in a third configuration of use, with all views identical to that of the first embodiment except of being non-transparent;

FIG. 16 is a top, front, left side perspective view of a drawer unit, showing a third embodiment of our new design in a first configuration of use;

FIG. 17 is a top, front, left side perspective view thereof, shown in a second configuration of use;

FIG. 18 is a bottom, back, left side perspective view thereof;

FIG. 19 is a front view thereof;

FIG. 20 is a back view thereof;

FIG. 21 is a left side view thereof;

FIG. 22 is a right side view thereof;

FIG. 23 is a top view thereof;

FIG. 24 is a bottom view thereof;

FIG. 25 is a top, front, left side perspective view thereof, shown in a third configuration of use;

FIG. 26 is a bottom, back, left side perspective view thereof;

(Continued)

FIG. 27 is an enlarged view of detail 27 in FIG. 25;
 FIG. 28 is an enlarged view of detail 28 in FIG. 26;
 FIG. 29 is an exploded perspective view thereof;
 FIG. 30 is a top, front, left side perspective view drawer unit, showing a fourth embodiment of our new design in a third configuration of use, with all views identical to that of the third embodiment except of being non-transparent; and,
 FIG. 31 is a top, front, left side perspective view of a drawer unit, showing a fifth embodiment of our new design, a stacked configuration of the first and third embodiments. The broken lines depict portions of the article that form no part of the claimed design.

Dot dash lines in FIGS. 10-13 and 25-28 are used to mark boundary of areas of enlargement, and form no part of the claimed design.

The “Vtopmart” in broken lines on handles of the drawer units, does not form part of the claimed design and is a registered trademark, with U.S. Reg. No. 7,613,706 and 7,713,707. The owner of the registered trademark is Shenzhen Yihong Technology CO., LTD, Baoyuan Rd, Xixiang St., Bao'an Dist. B610, Bldg 1, Zone A, Internet Base, Shenzhen, China 518000.
